Des. Re. 19,866

UNITED STATES PATENT OFFICE

19,866

DESIGN FOR A KNITTED CAP OR SIMILAR ARTICLE

Alex Epstein, Brooklyn, N. Y., assignor to Epstein & Hammer, Inc., Brooklyn, N. Y., a corporation of New York

Original No. 86,360, dated March 1, 1932, Serial
No. 39,866, May 16, 1931, for 3½ years. Application for reissue October 14, 1933, Serial No.
49,480. Term of patent 14 years

To all whom it may concern:

Be it known that Alex Epstein, a citizen of the United States and resident of Brooklyn, in the county of Kings and State of New York, has invented a new, original, and ornamental Design for Knitted Cap or Similar Article, of which the following is a specification, reference being had to the accompanying drawing, forming part thereof, in which,

Fig. 1 is a perspective view of a knitted cap embodiment my new design; and
Fig. 2 is a side elevational view thereof.

I claim:—

The ornamental design for a knitted cap or similar article, substantially as shown.

Dated, October 9th, 1933.

ALEX EPSTEIN.
